UNITED STATES PATENT OFFICE.

JAMES H. KELLER, OF FORT MYERS, FLORIDA.

PIPE-STANDARD.

1,331,930.

Specification of Letters Patent. Patented Feb. 24, 1920.

Application filed May 21, 1918. Serial No. 235,804.

To all whom it may concern:

Be it known that I, JAMES H. KELLER, a citizen of the United States, residing at Fort Myers, in the county of Lee and State 5 of Florida, have invented certain new and useful Improvements in Pipe-Standards, of which the following is a specification.

This invention has relation to supports for tanks, cisterns or the like, and especially 10 for the type having a depending, conical bottom; and has for an object to provide a support of this character embodying many new features of design, calculated to afford a rigid and substantial support with a minimum 15 amount of material.

Another object of the invention is to provide a support of the character described, formed in parts which may be readily assembled at the place of installation, at the same time enabling the support to be more 20 conveniently shipped.

In addition to the foregoing, this invention comprehends improvements in the details of construction and arrangement of 25 parts, to be hereinafter described and particularly pointed out in the appended claim.

In the accompanying drawings, in which similar and corresponding parts are designated by the same characters of reference, 30 throughout the several views in which they appear:

Figure 1 is a view in side elevation of an improved tank support, constructed in accordance with my invention, and

Fig. 2 is a view thereof in plan.

With reference to the drawings, 10 indicates (in dotted lines), the tank to be supported, and 11 the conical bottom thereof.

The support comprises three, four or more 40 uprights, or standards, each having its ends apertured, each upright being indicated generally 12. Each standard is supported upon a concrete foundation or footing 14, and a base plate 15 is supported upon each foot- 45 ing. Each base plate is formed with an up- standing lug 16 which enters the lower aperture of a standard.

Each standard furthermore comprises a 50 triangular bracket 18, comprising a vertical stand, an inclined arm 20 which extends inwardly and downwardly, and an inclined strut 21 forming a brace for the other two

sides. The lower end of the stand 19 is formed with a depending lug 22 which enters the upper aperture of the section 17. 55 The upper end of the stand 19 is recessed to form a ledge 23 upon which an annular member 24 is supported as shown. The lower end of each arm is also recessed to afford a support for a second annular mem- 60 ber 25, smaller than the first, and by reason of its points of support, is located beneath the first annular member and in concentric relation thereto.

From the foregoing it will be obvious 65 that the bottom edge of the straight wall of the tank may be supported upon the annular member 24, and the lower end of the conical bottom will be held within the sec- 70 ond annular member 25. It will further- 75 more be apparent that I have provided an extremely simple form of support for the purpose intended. One in which the parts may be readily disassociated and as readily assembled. The triangular members may be 75 packed together in compact formation with the standards and other parts. Other ad- 80 vantages will occur to those familiar with the art to which this invention appertains.

Having thus described my invention, what 80 I claim as new and desire to secure by Let- 85 ters Patent is:

A support of the class employed to sup- 85 port a conical bottomed tank, including a plurality of supporting standards each hav- 90 ing its ends apertured, a base plate having an upstanding lug arranged to fit into an aperture, a bracket detachably secured to each of said standards including a stand 95 having a lug projecting from its lower end arranged to seat in an aperture, a down- wardly directed arm extending from each stand, a strut extending from the lower end of each arm to the lower end of the connect- ed stand, each stand and arm having a ring receiving seat, a ring in said arm seats and a ring in said stand seats, all arranged as and for the purpose set forth.

In testimony whereof I affix my signature in the presence of two witnesses.

JAMES H. KELLER.
